UNITED STATES PATENT OFFICE.

CHARLES F. ROPER, OF HOPEDALE, MASSACHUSETTS, ASSIGNOR TO
DRAPER COMPANY, OF HOPEDALE, MASSACHUSETTS, A CORPORA-
TION OF MAINE.

TAKE-UP MECHANISM FOR LOOMS.

SPECIFICATION forming part of Letters Patent No. 716,282, dated December 16, 1902.

Application filed February 8, 1902. Serial No. 93,203. (No model.)

To all whom it may concern:

Be it known that I, CHARLES F. ROPER, a citizen of the United States, and a resident of Hopedale, county of Worcester, State of Massachusetts, have invented an Improvement in Take-Up Mechanism for Looms, of which the following description, in connection with the accompanying drawings, is a specification, like numerals on the drawings 10 representing like parts.

This invention relates more particularly to the means for taking up the cloth as it is woven on a loom; and one of the objects of my invention provides for a very simple, direct- 15 acting, and effective take-up mechanism.

The novel features of my invention will be hereinafter described, and particularly pointed out in the following claims.

Figure 1 is a front elevation of a portion of 20 a loom at the left-hand side thereof with one embodiment of my invention applied thereto. Fig. 2 is a side elevation of the mechanism shown in Fig. 1 viewed from the left. Fig. 3 is a detail, partly in section, on the line 25 3 3, Fig. 1. Fig. 4 is a side elevation of the actuating-pawl, and Fig. 5 is an inner face view of the ratchet with which the pawl cooperates.

Referring to Figs. 1 and 2, the loom side 1, 30 breast-beam 2, the lay 3, and lay-sword 4, fulcrumed on the shaft 5, supported on the loom sides, the controlling or operating rock-shaft 6, mounted in suitable bearings below the breast-beam and having an upturned arm 7 in the path of movement of the outer end of 35 the weft-fork slide of well-known construction and not herein shown, may be and are all of usual construction and operate in well-known manner. The controlling rock-shaft 40 6 corresponds to the rock-shaft d^x in United States Patent No. 659,628, dated October 9, 1900, rocking of such shaft by or through an abnormal condition of the filling operating in my present invention to arrest the action of 45 the take-up mechanism, as will appear more fully hereinafter.

The core or bar 8, upon which the roll of cloth 9 is wound, is mounted in suitable bearings in stands, one of which is shown at 10,

Figs. 1 and 2, and forming no part of my 50 present invention.

The take-up or "sand" roll 11, as it is sometimes called, has its shaft 12 supported in suitable bearings, one of which, as 13, is shown in Figs. 1, 2, and 3 as forming part of a bracket 55 14, suitably secured to the loom side, the end of the shaft extended through said bearing having rigidly attached to it a worm-gear 15. The worm-gear is in mesh with and is driven by a worm 16, fast on a shaft 17, rotatably 60 mounted in bearings 18 on the bracket 14, as clearly shown in Fig. 3, the front end of said shaft being extended forward beyond the bracket and having a polygonal portion 19 adjacent its threaded end 20. A ratchet, 65 shown as a disk 21, having a series of circumferentially-arranged teeth 22 on its inner face, has a hole 23, Fig. 5, corresponding to the cross-section of the part 19 of the worm-shaft, and said ratchet is mounted thereon, being held 70 securely in place against a shoulder 24 on the shaft by a suitable washer 25 and nut 26. (Best shown in Fig. 3.) Between the inner face of the ratchet and the adjacent bearing 18 an actuating-pawl 27 (see Fig. 4) 75 is pivotally mounted on the shaft 17, said pawl having an elongated opening 28 therein, through which the shaft passes. The pawl has a tooth or lug 29 to coöperate with the teeth of the ratchet, and above said 80 lug I have shown two projections 30, which are adapted to engage the inner face of the ratchet within the series of teeth thereon, and said pawl has a laterally-extended and rearwardly-bent guide-arm 31 and a depend- 85 ing finger 32 for purposes to be described. A spring 33, coiled about the shaft 17 between the pawl and the adjacent bearing 18, yieldingly maintains the pawl in coöperative engagement with the ratchet. A link 35 is piv- 90 otally connected at its upper end at 34 to the lateral arm 31 of the pawl, the lower end of said link passing loosely through a boss 36 on an arm 37, rigidly attached to the lay-sword 4, as clearly shown in Figs. 1 and 2. 95 Collars 38 39 are adjustably secured to the link above and below the boss 36, respectively, and so located that when the lay beats up

the arm 37 swings down and causes the boss 36 to engage the collar 39, and thereby pull the link 35 downward. This rocks the pawl in the direction of the arrow 40, Fig. 4, and 5 turns the ratchet and its attached shaft, thereby giving a partial turn to the worm, and thence through the worm-gear 15 the take-up roll is turned to take up the cloth as it is woven. This intermittent or step-by-step rotation of the ratchet and take-up roll continues while the loom is running, and the cloth is gradually and positively taken up and wound on the bar 8. When the lay swings back, the boss 36 rises and engages the collar 15, lifting the link 35 to swing the pawl back to starting position to engage a new tooth of the ratchet, and as the lug 29 rides over the tooth or teeth of the ratchet the spring 33 is compressed, the pawl tipping on the shaft 17 20 and being supported by the engagement of the projections 30 with the inner face of the ratchet 21. The guide-arm 31 travels on the upright face of the loom side and serves to guide and steady the pawl when it is swung back and forth.

25 By substituting ratchets having different numbers of teeth the angular movement of the worm at each beat of the lay can be varied as desired, the collars 38 and 39 being 30 adjusted to correspond, it being obvious that the greater the number of ratchet-teeth the shorter must be the stroke of the pawl if the ratchet is to be advanced one tooth at a time. If a ratchet be used with a large number of 35 teeth, the pawl can be made to advance the ratchet one or more teeth each stroke by adjusting the collars.

I have shown the controlling rock-shaft 6 provided with a bent and downturned arm 40 41, which extends in front of the finger 32 of the pawl and normally not engaging it; but when the said rock-shaft is turned upon the occurrence of an abnormal condition of the filling, such as breakage thereof or its substantial exhaustion in the shuttle, then the arm 41 is brought into engagement with the finger 32 and the pawl is tipped on the shaft 17, compressing the spring 33 and preventing engagement of the pawl-lug 29 with the 45 ratchet-teeth, so that the movement of the pawl by or through the motion of the lay will not operate the take-up until the rock-shaft 6 is returned to normal position. The tipping of the pawl just referred to is permitted 50 by the elongation of the opening 28. A finger-piece 42 is shown on the outer face of the ratchet to enable reverse rotation of the latter by hand if it is desired to let back the cloth.

60 From the foregoing specification, taken with the drawings, it will be manifest that I have eliminated the usual train of gearing between the take-up roll and the primary actuating device, and by so doing I not only 65 reduce parts and simplify construction, but I practically eliminate backlash and lost motion and transmit directly to the take-up roll

the action of its actuating device. The worm and worm-gear obviate the necessity for detent-pawl or other devices for preventing retrograde motion of the take-up roll, as the well-known self-locking action of the worm and worm-gear controls the take-up roll absolutely at all times.

Having fully described my invention, what I claim as new, and desire to secure by Letters Patent, is—

1. In take-up mechanism for looms, a take-up roll having an attached worm-gear, a worm in mesh with and to rotate the gear, a ratchet 80 on the worm-shaft, a coöperating pawl fulcrumed on the worm-shaft, a spring to yieldingly maintain the pawl in coöperative relation with the ratchet, and means to intermittently actuate the pawl.

2. In take-up mechanism for looms, a take-up roll having an attached worm-gear, a worm in mesh with and to rotate the gear, a ratchet-disk fast on the worm-shaft and having circularly-arranged teeth on its inner face, a 90 coöperating pawl fulcrumed on and adapted to tip on the worm-shaft, a lug and a projection on the pawl, on its face adjacent the ratchet-disk and on opposite sides of the worm-shaft, a spring to yieldingly maintain 95 the pawl in coöperative relation with the ratchet-disk, and means to intermittently actuate the pawl, the latter tipping and being supported by engagement of the projection with the ratchet-disk as the lug rides over a 100 ratchet-tooth on the retractive stroke of the pawl.

3. In take-up mechanism for looms, a take-up roll, a rotatable shaft, connections between it and the take-up roll, to rotate it by 105 or through rotation of the shaft, a ratchet on the shaft, a coöperating pawl fulcrumed on the said shaft, a spring to yieldingly maintain the pawl in coöperative relation with the ratchet, and means to intermittently actuate the pawl.

4. In take-up mechanism for looms, a take-up roll, a rotatable shaft, connections between it and the take-up roll, to rotate it by or through rotation of the shaft, a ratchet-disk 115 on the shaft, having circularly-arranged teeth on its inner face, a coöperating pawl fulcrumed upon and adapted to tip on the shaft adjacent to the disk, a spring to yieldingly maintain the pawl in coöperative relation with the ratchet-disk, said pawl having a lug on its face to engage the ratchet-teeth, and means to actuate the pawl, retraction thereof causing it to tip on the shaft to permit its lug to ride over the ratchet tooth or 120 teeth.

In testimony whereof I have signed my name to this specification in the presence of two subscribing witnesses.

CHARLES F. ROPER.
